HARRY LYON, OF HOLBROOK, MASSACHUSETTS, ASSIGNOR TO PERLEY E. BARBOUR,
OF QUINCY, MASSACHUSETTS, DOING BUSINESS AS BARBOUR WELTING COMPANY

TWO-UNIT WELTING

Application filed January 7, 1928. Serial No. 245,209.

This invention relates to welting and more particularly to the manufacture of two-unit welting known to the trade by the general designation "cork-sole" or simply "calk"

5 welting.

The characteristic feature of cork-sole welting consists of a unit secured to the inner margin of the upper face of a strand of Goodyear or similar welting so that when the welting 10 is built into a shoe this top unit lies in the welt crease.

Heretofore the top unit has been formed of a strip of low grade material requiring a covering strip to give it a finish comparable 15 to the finished parts of a shoe adjacent which it lies. The object of the present invention is to produce a two-unit welting that will provide the requisite finish without the addition of covering material.

20 To the achievement of this object the invention comprises a novel method of forming the top-unit; a novel mode of preparing and assembling simply the two units to complete a two-unit welting; and the novel two unit 25 welting as an article of manufacture, as hereinafter described and then particularly pointed out in the appended claims.

The preferred form of the invention is illustrated in the accompanying drawings, in 30 which:

Figure 1 is a view, in perspective, of one end of a piece of grain leather showing how top units are severed therefrom;

Fig. 2 is a view, in perspective, of one end 35 of a strip forming a top unit prepared for securing to a bottom unit to complete the novel welting;

Fig. 3 is a view, in perspective, of one end 40 of a strand of two-unit welting prepared by practising the process of this invention; and

Fig. 4 is a view, in perspective, of a portion 45 of a shoe into which welting having the characteristic features of this invention has been built.

The cork-sole welting produced under the teaching of this invention is strictly a two-unit welting, i. e. it consists of the top and bottom units and no more. At the same time the mode of producing the top unit and the 50 mode of assembling the two units is such that

the requisite finished appearance in the completed shoe is obtained without the necessity of incorporating a third element such as a covering strip for the top unit.

In the embodiment of the invention illustrated in the drawing the top and bottom units of the welting are designated 10 and 12 respectively (Figs. 3 and 4). The bottom unit 12 may be the same, or substantially the same, as a strand of Goodyear welting having 60 a grain face 13, a stitch-receiving groove 14 in the opposite flesh face and a bevel 15 at its inner edge to promote flexibility in fitting the welting into the shoulder of the insole (see Fig. 4).

The top unit 10 is triangular, the cross-section preferably being that of a right-triangle, and it is produced as follows. A piece of flexible grain leather 16 (known as "welting leather") of indeterminate width and length, 70 is severed by parallel lengthwise cuts, so related to each other as to produce triangular strips 10 of the desired proportions. The bottom unit 12 may be of varying width and thickness to accommodate the requirements 75 of shoe manufacturers, but it is proposed to produce a top unit from the leather piece 16 of such proportions that it will function properly when assembled with any size of bottom unit. The dimensions selected as most desir-

able for the triangular top unit are a short (grain) side of $\frac{1}{8}$ " and a long (flesh) side of $\frac{3}{2}$ " at right angles to the short side, but these dimensions are not fixed and may be varied without departing from the invention. 85 Accordingly a leather piece 16 having a thickness of $\frac{5}{2}$ " is striped lengthwise by cuts 17, separated by $\frac{1}{8}$ " of grain which surfaces eventually form the grain faces 18 of the top unit strips, these cuts being parallel and per-

pendicular to the grain face so that there is a right-angle between the grain and the flesh exposed by the cut. The rectangular strips thus produced are then severed on a diagonal by parallel cuts 19 and the portions 20, having three flesh sides, are discarded as waste. Stripping the leather piece 16 in this manner produces a right-triangular strip 10 having a grain side face 18 that is $\frac{1}{8}$ " wide, a flesh side face 22 that is $\frac{3}{2}$ " wide and a flesh hy-

pothenuse face 24. The sequence and nature of the cutting steps in producing the strips 10 from the leather piece 16 is immaterial provided the described triangular top unit strip is eventually obtained.

5 The top-unit 10 is laid along the inner margin of the bottom unit 12 (see Fig. 3) with its widest face 24 against the grain of the bottom unit and with its grain side face 18 facing outward. This position causes the 10 flesh side face 22 to lie against the shoe upper 26 (see Fig. 4) when the welting is stitched to the shoe, and the soft, spongy nature of the flesh enables the calking strip 10 to yield and 15 conform to all inequalities of the welt crease and thus to hug the upper throughout its top edge.

Preferably the top unit or calk 10 is secured 20 to the bottom unit by a dry thread seam 28 which is hidden from view in the completed shoe. To provide a smooth face 22 to lie 25 against the upper the seam 28 is sunk into or buried in the surface, i. e. fudge-stitched, and to this end the face 22 is slit longitudinally 30 as at 30. Preferably the plane of the seam 28 is such that it lies outside the inseam 32 (Fig. 4).

The novel welting may be secured to the 35 insole 34 and outsole 36 of the shoe by usual methods.

When built into the shoe the welting presents a grain shoulder 18 in the welt crease comparable in finish to the adjacent grain 13 of the welt strand 12, and the upper edge of 35 the calk 10, or angle between its side faces 18 and 22, is conformed tightly and neatly to the upper, all without the use of any material other than welting leather. Either of the 40 flesh faces 22 or 24 may be laid against the upper to vary the style of the trim in the welt crease.

The nature and scope of the invention having been indicated and its preferred embodiment and method of manufacture having been 45 specifically described, what is claimed as new, is:—

1. All-leather two-unit welting consisting of a bottom unit substantially rectangular in cross-section having a grain face and a top-unit triangular in cross-section having one grain face, said top-unit being secured to the grain face of the bottom unit with its grain face facing outward.

2. All-leather welting consisting of two 55 units, one being a strand of grain Goodyear welting and the other being a strip of right-triangular cross-section cut from welting leather in a manner to preserve the grain on one of the side faces of the strip, said two 60 units being assembled with the strip lying with its hypotenuse face against the grain of the strand along the inner margin thereof and with its grain side face facing outward.

3. All-leather welting consisting of top and 65 bottom units, the top unit thereof comprising

a strip of triangular cross-section having one grain face and two flesh faces lying at the inner margin of the bottom unit with one flesh face in engagement therewith and its grain face forming an outwardly facing shoulder, 70 and fastenings along the inner flesh face of said strip passing from one unit into the other for securing them together.

4. All-leather welting consisting of top and bottom units, the top unit thereof comprising 75 a strip of triangular cross-section having one grain face and two flesh faces lying at the inner margin of the bottom unit with one flesh face in engagement therewith and its grain face forming an outwardly fac- 80 ing shoulder, and a thread seam fudge-stitched in the other flesh face of said strip and through said bottom unit.

5. In a two-unit welting a leather top-unit 85 of triangular cross-section, one face being from the grain and the other two faces being from the flesh, and one flesh face having a longitudinal slit therein to receive and bury a seam for securing the two units together.

6. The method of making all-leather two-unit welting which includes the steps of preparing a bottom unit strand of substantially rectangular cross-section from grain leather, preparing a top unit strip of triangular cross-section by severing a strip of quadrilateral 95 cross-section from grain leather and then dividing said strip on a diagonal, discarding the portion that has no grain face, then securing the triangular grain face strip to said strand in position to form an outwardly fac- 100 ing grain shoulder.

7. A welt shoe having an insole, an upper and a cork-sole welt secured thereto, the bottom unit of said cork-sole welt consisting of a strand of grain Goodyear welting and the top-unit consisting of a strip of triangular cross-section having one grain face and lying in the crease of the shoe with its grain face exposed and forming a continuation of the grain face of said bottom unit, said top and bottom units being secured together by concealed fastening means, and an outsole secured to the bottom unit of said cork-sole welt.
